UNITED STATES PATENT OFFICE.

EDUARD BOCK, OF BANGKOK, SIAM.

HIGH-LEVEL TRAMWAY.

SPECIFICATION forming part of Letters Patent No. 594,061, dated November 23, 1897.

Application filed July 10, 1897. Serial No. 644,143. (No model.) Patented in France September 10, 1895, No. 250,186; in Belgium October 14, 1895, No. 117,867; in Switzerland October 14, 1895, No. 11,363; in England October 15, 1895, No. 19,370; in Austria October 16, 1895, No. 45/4,530; in Hungary October 21, 1895, No. 4,450; in Norway October 23, 1895, No. 4,724; in Sweden December 19, 1895, No. 7,442; in Denmark December 21, 1895, No. 803, and in Italy December 28, 1895, 40,447/244.

To all whom it may concern:

Be it known that I, EDUARD BOCK, a subject of the Emperor of Austria-Hungary, residing at Bangkok, Siam, have invented new and useful Improvements in High - Level Tramways, (for which I have obtained Letters Patent in France September 10, 1895, No. 250,186; in Belgium October 14, 1895, No. 117,867; in Austria October 16, 1895, No. 45/4,530; in Hungary October 21, 1895, No. 4,450; in England October 15, 1895, No. 19,370 of 1895; in Sweden December 19, 1895, No. 7,442; in Switzerland October 14, 1895, No. 11,363; in Norway October 23, 1895, No. 4,724; in Italy December 28, 1895, No. 40,447/244, and in Denmark December 21, 1895, No. 803,) of which the following is a specification.

My invention relates to an improved system of high-level tramways and rolling-stock; and it consists principally of providing the vehicles with balloons to relieve the structure from practically all live loads, except such as is necessary to produce sufficient friction to propel cars along the supporting and guiding rails or cables.

The principal objection to elevated railways heretofore constructed is their immense cost of building, owing to the heavy rolling-stock propelled over the track, which necessitates deep foundations, heavy columns, cross and longitudinal girders and bracings, and besides this obstructing to a large degree the streets occupied by such railways.

In my improved overhead railway, in which the weight of the rolling-stock, cars, or other vehicles is principally carried by balloons attached to the same, the superstructure supporting the guide and carrying rails or cables may be safely made very light, reducing the cost thereof to a minimum and obstructing streets very little. Provision, however, must be made to safely guide and protect the vehicles or cars against wind-pressure.

My invention will be more fully understood taken in connection with the accompanying drawings, forming part hereof, in which—

Figure 1 is a longitudinal elevation of the

car, showing the means for attaching the balloon or balloons to a car, the sails for increasing the driving power, the guide and supporting cables or rails, and the guide-wheels engaging the latter. Fig. 2 is a transverse section of the railway, showing a car in position on the supporting and guide cables or rails and also showing the balloon attached to the top of the car, the special arrangement of the supporting and guide cables or rails, the means for transmitting power to the cars, and also staircases as access to the cars. Fig. 3 is a section on the line I II of Fig. 2, showing the lower part of the balloons and the top of the car with the sails taken in on one side and set on the other. Fig. 4 shows the detail construction of the mountings in which the guide-wheels of the vehicle are journaled.

Referring now to the drawings for a further description of my invention, M are the columns or posts of the superstructure, firmly held and supported in the ground and connected in the middle and at the top by struts d. Corner - brackets may be employed to stiffen the posts transversely, and tie-rods (not shown) may be used to brace the columns or posts longitudinally, so as to transmit the strains due to wind-pressure, running and braking of cars, to the foundations of the columns. To the struts or cross-girders d are suitably fastened arms a, to which the supporting and guide cables or rails s are secured. In the drawings are shown eight of such supporting and guide cables or rails s s' s'', one of which, s'', is arranged for the driving-wheels below the cars, two (marked s') on each side of the car and at about the height of the ceiling of the car, and five guide cables or rails s at the top of the balloon or balloons. It will, however, be understood that any other number of cables or rails may be employed and placed at positions different from those shown.

Platform-stations may suitably be arranged along a railway of my improved system and be accessible by staircases, as shown in Fig. 2.

The cars or vehicles V to be propelled electrically over such railway are constructed as light as possible and in any desired shape, with vestibules for the motorman, benches 5 for the passengers, &c. Each car V is provided with frictional driving-wheels o, arranged below the bottom of the car and driven by gear-wheels from suitable electric or other motors e, situated under the benches. On 10 the sides of the cars and at about the ceiling thereof are arranged other wheels o' to further support and guide the car V by the cables s'.

Each car V is provided with one or more 15 sections of a balloon B to carry the greater portion of the weight of the car to relieve the superstructure from most all live load, except so much as is necessary to produce sufficient friction for the propulsion of the car 20 V by the motors e and driving-wheels o. The balloon is made in two or more sections or divided into two or more compartments, so that if one section is mutilated or useless the other compartments are still intact and avoid 25 accidents. The balloon B is made of any suitable material, pointed at both ends to reduce the resistance offered by the air and secured to the top of the car V by the steel bands r, which latter brace and stiffen the 30 balloon-cover. On certain of the steel bands r are provided guide rollers or wheels p, engaging the upper guide cables or rails s. These guide-wheels p, as well as the wheels o, are journaled in the spring-arms m, secured 35 to the frame of the car and balloon-stays r, as shown in detail in Fig. 4. The arms m are bent at their free extremities and are provided with the buttons k, which normally abut each other and at all times inclose the 40 respective cables or rails s to insure safety. Whenever in the propulsion of the car the arms m come in contact with the cable or rail support a, the former yield outward and let the latter pass between, after which the buttons k again abut.

As before stated, preference is given to electric motors to propel the cars along the railway, and it may here be remarked that cer-

tain of the cables or rails s or s' may be used as conductors.

For increasing the power of the driving-motor the cars may be supplied with sails t, fastened to vertical posts z in such a manner that they may be unrolled around those posts entirely or partly when the wind would blow 55 too violently to use them.

It will be understood that modifications may be made in the detail construction and arrangements of the superstructure as well as of the cars, and I desire it to be understood 60 that modifications can be made without departing from the spirit of the invention.

Having thus described the nature and objects of my invention, what I claim as new, and desire to secure by Letter Patent, is— 65

1. An overhead railway comprising a superstructure composed of posts connected by two transversely-disposed struts, a cable carried by the lower strut to partly support the rolling-stock, a car provided with guide and driving wheels adapted to engage the said cable, a compartment-balloon attached to the car and serving to carry the greater portion of the weight of the car, guide-wheels journaled to the frame of the balloon and engaging the 70 cables suspended from the upper strut of the superstructure, substantially as and for the purposes set forth.

2. In an overhead railway comprising a superstructure composed of posts, transverse struts, cable-supports a and cables, in combination with a car-body supported by a balloon and the said cables, of driving and guide wheels for the said car-body and balloon, said wheels journaled in bearings having yielding 85 ends to allow for the passage of the cable-supports a when the car with its balloons is in motion, substantially as and for the purposes set forth.

Signed at Bangkok, Siam, this 12th day of 90 May, 1897.

EDUARD BOCK.
